Primary Examiner—James Gandy*Assistant Examiner*—Stacia Sinuik*Attorney, Agent, or Firm*—Brooks & Kushman P.C.[57] **CLAIM**

The ornamental design for a removable storage container for motor vehicle, as shown and described.

DESCRIPTION

FIG. 1 is a top front perspective view of a removable storage container for motor vehicle showing my new design;

FIG. 2 is a front elevation view thereof;

FIG. 3 is a rear elevation thereof;

FIG. 4 is a bottom view thereof;

FIG. 5 is a top view thereof;

FIG. 6 is a left side view thereof; and,

FIG. 7 is a right side view thereof.

The broken line showing of environment is for illustrative purposes only and forms no part of the claimed design.
